GRAHAM KING, OF SOUTH ORANGE, AND FRANK A. HOWARD, OF RIDGEWOOD, NEW JERSEY, ASSIGNEES TO TRUSCON STEEL COMPANY, OF DETROIT, MICHIGAN, A CORPORATION OF MICHIGAN

COMPOUND DOOR

Application filed November 25, 1925, Serial No. 71,488. Renewed October 24, 1928.

This invention relates to doors and more particularly to a class of doors wherein two or more sections are used in cooperation with one another to form a compound door for closing an opening larger than any one of the sections.

Among the objects of our invention is to produce a compound door suitable for use as a pier door, and for closing any large door opening, such as is found in warehouses, freight depots and other commercial sheds and buildings.

Another object of this invention is to produce a compound door of which the lower or minor sections may be successively raised and opened prior to the opening of the upper or major section and in which the major section may be opened at the termination of the opening movement of the minor sections and as a result of the continuing effort exercised in carrying out the operation of opening the minor sections whereby the entire compound door may be opened by a single continuous and uninterrupted operation.

Another object resides in providing mechanism which will enable a continuous opening movement of a compound door to be carried out and, also, which will permit of a partial opening of a minor section, and of the major section, depending upon the stage to which the opening operation has progressed, without the necessity of relying upon other mechanism for maintaining the particular section or sections of the compound door partially opened or in its or their existing stage of opening operation.

Another object is to provide mechanism which will insure the complete closure of an upper part of an opening by a major section of a compound door prior to the closure of the lower part of an opening by a minor section of the compound door.

Other and more detailed objects will appear hereinafter in the accompanying specification and claims and are shown in the drawings which, by way of illustration, show one and a preferred embodiment of the invention.

In the drawings:

Fig. 1 is perspective view of a portion of

a compound door together with mechanism employed for operation of the door.

Fig. 2 is a transverse view of the door showing the minor section in a raised position, and the major and minor sections in an inclined position.

Fig. 3 is a complete elevation of the compound door as seen from the inside and in its closed position.

Fig. 4 shows a detail of construction on line 4—4 of Fig. 3.

Fig. 5 shows a detail of construction on line 5—5 of Fig. 3.

In general, the compound door illustrated comprises two sections, a major section 10 and a minor section 11. The major section 10 is supported along its upper edge 12 by means of a plurality of hinges 13 which are, in the present embodiment, secured to the inner side of the door frame 14 so as to permit the door to be swung inwardly or within the building in a manner to be hereinafter described. The closed position of section 10 is illustrated in Figs. 1 and 3, and Fig. 4 illustrates how the edge frames 15 of this section contact with the sides of the door frame. The sides of the door frame may be made satisfactorily of structural steel, and an angle-iron 16 may serve the purpose of preventing outward movement of the section.

In its closed position, the minor section 11 rests upon the floor or door sill and it is maintained in a vertical position by means of a guiding channel 17 which is permanently located on the lower part of each edge of the door frame. The edges 18 of the minor section are adapted to slide loosely within the channel and the upper ends 19 of the channel may be flared or enlarged in order to permit easy entrance of the edges.

On the vertical edges of the major section 10 are secured angle-irons 20, ends of which are so disposed as to form a channel in coaxial alignment with the channel just described when the major section is in its closed position. Figs. 1, 4 and 5 clearly show that section 11 may be raised from its closed position, maintained by channel 17, to a position directly above its closed position and in ad-

ja⁵cent relation to the major section 10, the outwardly extending legs of angle-irons 20 guiding and maintaining the minor section close to the major section.

5 The movements of the door sections may be accomplished by means of ropes or cables passing over sheaves and power may be applied to control the ropes or cables by any suitable means. For simplicity in description we have illustrated a hand winch as a conventional indication of a suitable source of power. In the present embodiment the winch 21 is located near to the left edge of the door opening and a rope 22, of which 10 one end 23 is secured to the lower edge of the frame of section 11 by a bracket and of which the other end 24 is fastened to a counter-weight 25, encircles the drum of the winch.

15 The course of the rope from its end 23 leads upward and over sheave 26 which is mounted on a bracket 27 fastened to angle-iron 20 at the left edge of the major section, over sheave 28 permanently located close to the ceiling or the limit of extreme opening 20 of section 10, over sheave 29, downward and around the drum of winch 21, upward and over sheave 30 which is mounted upon a bracket extending from a column, downward and around sheave 31 also mounted 25 upon a bracket extending from a column, under sheave 32 mounted upon bracket 27 fastened to the left vertical edge of frame 15, upward and over sheave 33 mounted upon a column, and downward to the end 24 30 secured to the counter-weight.

35 When the winch is operated to allow the counter-weight to descend, the minor section 11 will be raised vertically upward and guided first in channel 17 and then by both 40 channel 17 and the channel formed by angle-iron 20. As long as edge 18 is in engagement with channel 17, the minor section will be raised and the horizontal component of the pull of rope 22 on sheave 26 will be ineffectual to cause any change of condition of 45 the major section. However, when section 11 has been raised away from the restraining influence of channel 17 and has passed the end 19, the force exerted by rope 22 upon 50 sheave 26 will be effective to swing the major section on its hinges 13 so as to swing and raise both of the sections to any angle desired, as illustrated in Fig. 2, or to its highest position as limited only by the position 55 of support of sheave 28. The vertical rising movement of section 11 is immediately followed at its termination by the swinging movement of both of the sections and there is no break in the continuity of movement 60 of the rope. If a small opening of the door is desired, the minor section would be raised only to the amount desired, the edge of channel 17 effectually serving to maintain the major section closed by the interlocking effect 65 of the minor section and the channel.

Where the occasion would require or the condition of the weather necessitate, the two sections may be maintained at any angle desired, for example, as is shown in Fig. 2. At this angle, or at any other angle or position 70 of the sections of a door the sections will remain where positioned because of the compensating force exerted by the counter-weight. When used as a pier door, the sections may be left in the position indicated 75 in Fig. 2 so that hoists and tackles could be swung within the building with a minimum amount of opening and the counter-weight and cooperating-mechanism would maintain the door in a state of equilibrium. The 80 function of the winch is to control the positioning of the sections and of the counter-weight and to aid in maintaining the sections in position at any stage of opening or closing 85 operation.

For closing the door from its wide open position, the winch is operated in a direction opposite to that described and the length of rope between sheave 31 and sheave 32 will be shortened as the combined effort of the 90 winch, and weights of the door and counter-weight operates to draw the door to. As may be understood from a study of Fig. 2, it is evident that the effect of these forces upon the door will result in swinging the door to a vertical position. The pull upon the rope is continuous and the major section is thereby brought hard up against the door jamb in its closed position. While the door has been thus swung to, the counter-weight has descended to some extent, but as soon as further swinging of the door is prevented by the door jamb, the unwinding effect produced by the winch must be taken up by a rising of the counter-weight and a corresponding drop 95 of the lower or minor section 11. The major section being in its closed position, the minor section will descend with its vertical edges 18 guided by channel 17. Further operation of the winch will cause the lower section to be lowered until the entire door opening is closed, Fig. 1.

The foregoing is a brief description of the mode of operation of a compound door comprising details of the subject matter of our invention, and the mechanism described is sufficient to operate and control certain forms of doors depending upon size and strength, but we have found it advantageous to provide mechanism which will transmit parallel motion to both edges of a large and cumbersome door. Such mechanism is illustrated in Fig. 3, and partly illustrated in Figs. 1 and 2.

For the purpose of obtaining the parallel motion desired and also for transmitting the application of equal operating forces on both sides of the door, a continuation of the same rope could be used, but in the present embodiment another rope 220 is provided. Rope 100

220 is wound around the drum of the same winch that rope 22 is wound around so that the linear velocity of the two ropes are equal when the winch is being operated. One end 5 230 of rope 220 is secured to the lower edge of the frame of section 11 at its right end by a bracket and the other end 240 is secured to a counter-weight 250, similar to counter-weight 25, and disposed at the opposite edge 10 of the door opening. The course of the rope from its end 230 is over sheave 260, which is mounted on a bracket 270 fastened to angle-iron 20 at the right edge of the major section, over sheave 280 permanently located close to 15 the ceiling or limit of extreme opening of section 10, around sheave 34 and over and above the door opening to sheave 35, around the drum of the winch and upward and over sheave 36, above the door opening to sheave 20 37, downward and under a sheave (not shown), mounted upon a bracket extending from a column, under sheave 320, mounted upon bracket 270 fastened to the right vertical edge of frame 15, upward and over 25 sheave 330 mounted upon a column, and downward to the end 240 secured to the counter-weight 250. By the use of two counter-weights 25 and 250 the compensating weight will be divided equally between 30 them. It is readily understood that the ends 23 and 230, 24 and 240, travel at the same rate when the winch is operated and that each pair of ends define a line parallel to the lower edge of the lower section. The rope 35 referred to in the description may be of any material suitable for carrying out the purpose for which it is used, and enough turns must be made of each rope around the drum of the winch to overcome slippage, the 40 number of turns is, of course, dependent upon the coefficient of friction of the material used. A sprocket wheel and chain would serve satisfactorily.

Throughout the description, we have referred to a major section as defining the upper section illustrated, and we contemplate that a plurality of lower or minor sections could be controlled by the same set of ropes as herein described since each minor 50 section could carry a set of guiding channels and sheaves for controlling the rise of the minor section immediately therebelow, the rope being tied to the lower edge of the lowest section.

While the form of mechanism herein shown and described is admirably adapted to fulfill the objects primarily stated, it is to be understood that it is not intended to confine the invention to the form of embodiment 55 herein disclosed, for it is susceptible of embodiment in various forms, all coming within the scope of the claims which follow.

What we claim is:

1. In a compound door, in combination, a 60 door comprising a plurality of sections of

which a minor section is displaceable relative to a major section, means for pivotally supporting said major section, means to guide said minor section in its movement relative to said major section, and mechanism including a flexible member to control the movement of said minor section relative to said major section, and to swing said major section upon said first named means, said last named mechanism including a pair of elements with which said flexible member 70 75 acts for automatically completing the closing swinging movement of said major section.

2. In a compound door, in combination, a door comprising a plurality of sections displaceable relative to each other and relative to a door opening, means for sliding a lower section onto an upper section and for opening said upper section, said means comprising a flexible member having one end connected to the lower section and passing over a plurality of sheaves, one of which is mounted on said door and another of which is fixedly mounted near to the door opening substantially opposite the sheave on the door when the door is closed, whereby the movement of said flexible member during a door closing operation assists said door to be drawn tightly into closed position 80 85 90

3. In a compound door, in combination, a door comprising a major section and a minor section, said minor section being displaceable relative to said major section, means for displacing said minor section relative to said major section and for moving said major section, said means comprising a flexible member having a portion thereof extending between a sheave on said door and a sheave at the door opening, a counterweight connected to the end of said flexible member beyond the sheave on the door, and means for applying force to said flexible member between said two sheaves during a closing movement of said major section for bringing said major section close up against its door jamb. 95 100 105 110

4. A door of the class described comprising, in combination, a hinged upper section; a lower section adapted to slide into overlapping relation with said upper section; power applying means; a counter-weight; and door operating mechanism comprising, flexible means connected with the door and passing over a plurality of sheaves, the path of said flexible means extending from one end thereof, over a sheave on said upper section, a 115 sheave mounted away from the door opening and above an open position of the door, to and from said power applying means, a sheave mounted at the door opening, a sheave 120 mounted on the door, and to said counter-weight. 125

5. A door of the class described comprising, in combination, a hinged upper section; a lower section adapted to slide into overlapping relation with said upper section; 130

flexible means for raising said lower section into coincidence with said upper section and for swinging both of said sections; a plurality of sheaves for guiding said flexible means; said flexible means passing over one of said sheaves mounted on the door and another of said sheaves mounted at the door opening, these two sheaves being so related that the portion of said flexible means intermediate said two sheaves will be under tension and create a horizontal component of force tending to urge the door towards the door opening; and means for controlling the direction of movement of said flexible means.

6. A door of the class described comprising, in combination, a hinged upper section; a lower section adapted to slide into overlapping relation with said upper section; a counter-weight, flexible means for operating said door; and means for controlling the direction of movement of said flexible means; said flexible means being connected with the door and with said counter-weight and under the control of said controlling means, the length of said flexible means including an intermediate portion extending between a sheave on the door and a sheave at the door opening, said two sheaves being mounted so as to be opposite each other when the door is closed, one of the portions of said flexible means beyond said intermediate portion extending to said counter-weight, and the remaining portion of said flexible means extending to said controlling means and to said door.

7. Apparatus for operating a sectional door having one section slidable relative to another section and both sections adapted to be swung into positions away from a door opening comprising, in combination, flexible means connected with the lower section; means for guiding said flexible means and comprising a sheave on the upper section, a sheave positioned away from the door opening and above an open position of the door, a sheave at the door opening, and a sheave on the door; a force exerting means for maintaining said flexible means taut; and means for controlling the direction of movement of said flexible means during door opening and closing operations.

8. Apparatus for operating a sectional door having a lower section slidable relative to an upper section and both sections adapted to be swung into positions away from a door opening comprising, in combination, flexible means connected with one of the sections; means for controlling the direction of movement of said flexible means; a counter-weight; means for guiding said flexible means including a sheave on the upper section and a sheave at the door opening substantially opposite the sheave on the upper section when the door is closed whereby a portion of said flexible means always extends

from the door opening to the door in any position of the door and continually exerts a closing effect upon said door.

9. In combination, a door, operating mechanism for said door comprising, a flexible member with one end thereof having connection with said door, guiding means for training said flexible member including a guiding element on said door whereby a portion of said flexible member is caused to extend from said guiding element in a direction transverse to the plane of the door and to a position adjacent the door opening of said door, means for exerting a force upon said flexible member, and power applying means for controlling the opening and closing operations of said door by controlling the movement of the end of the flexible member having connection with said door.

10. In combination, a door, operating mechanism for said door comprising, a flexible member having one end associated with said door in such a manner as to be guided in a direction resulting from two combined movements transverse to each other, means for controlling the operation of said door through movement of said end of said flexible member resulting from said two combined movements, means for training said flexible member so as to cause it to travel desired paths, said means including a guiding element carried by said door from which a portion of said flexible member extends to a position adjacent the door opening of said door, means for exerting a force upon said flexible member whereby the tension created in the portion of said flexible means passing over said guiding element tends to urge the door towards the door opening.

11. In combination, a door, operating mechanism for said door comprising, a flexible member having one end associated with said door and having a combined vertical and lateral movement during a door closing operation, means for training the course of said flexible member during movement of the door, said means being so disposed as to cause a portion of said flexible member to extend from said door to a position adjacent the door opening of said door, the direction of said portion of the flexible member being such as to afford exertion of a horizontal component of force along its length, a force exerting means associated with said flexible member so as to exert tension upon said portion thereof, and means for controlling the direction of movement of said end of said flexible member associated with the door in one direction during a door opening operation and in a substantially opposite direction during a door closing operation during which the door may be affected by the force transmitted by said force exerting means tending to urge the door against its door jamb.

12. The combination with telescoping door

members having a pivotal mounting on which they can be swung, of means connected to the door members for effecting the telescoping action of the members and causing their positive pivotal movements in opposite directions to carry them to and from a fully open position and against wind resistance on the latter movement.

13. The combination with telescoping door members having a pivotal mounting on which they can be swung, of means connected to the door members for effecting the telescoping action of the members and causing their positive pivotal movements in opposite directions to carry them to and from a fully open position and against wind resistance on the latter movement while maintaining the sections in telescoped relation.

14. The combination with a swinging door section, of a sliding door section that telescopes the same, and operating mechanism for the door sections including means for causing the sliding door section to telescope the swinging door section, and devices on opposite sides of the swinging door section for positively swinging it in both directions.

15. The combination with a swinging door section, of a sliding door section that telescopes the same, and operating mechanism for the door sections including means for causing the sliding door section to telescope the swinging door section, and devices on opposite sides of the swinging door section and connected to its free end portion for positively swinging it in both directions.

16. The combination with an upper swinging door section hinged at its upper end, of a lower door section that is slidable to and from a telescoped position on the upper section, a winch for sliding the lower door section and swinging the upper door section, and cables wrapped oppositely around the winch and extending to the upper door section from opposite directions to positively swing it in opposite directions, one of said cables being also connected to the lower door section to slide it.

17. The combination with door members capable of telescoping movements and having a pivotal mounting on which they can be swung, of reversely movable actuating mechanism, and means connected to the members and operated by the actuating mechanism to effect their telescoping movements and their positive pivotal movements in opposite directions to carry them to and from a fully open position and against resistance during the latter movement.

18. The combination with door members capable of telescoping movements and having a pivotal mounting on which they can be swung, of reversely movable actuating mechanism, a means operated by the actuating mechanism when moved in one direction and connected to one of the members for effecting the telescoping movements of the members

and causing them to swing in one direction while telescoped, and a means also operated by the actuating means when moved in an opposite direction and connected to one of the members for positively swinging said members in an opposite direction.

In testimony whereof we hereto affix our signatures.

GRAHAM KING.
